UNITED STATES PATENT OFFICE.

FRANCIS H. STILLMAN, OF NEW YORK, N. Y.

HYDRAULIC RIVETING-TOOL.

SPECIFICATION forming part of Letters Patent No. 641,162, dated January 9, 1900.

Application filed May 19, 1899. Serial No. 717,439. (No model.)

To all whom it may concern:

Be it known that I, FRANCIS H. STILLMAN, a citizen of the United States, residing in the city of New York, borough of Brooklyn, in the county of Kings and State of New York, have invented a certain new and useful Improvement in Hydraulic Riveting-Tools, of which the following is a full, clear, and exact description, reference being made to the accompanying drawings, forming part of this specification.

This invention relates to improvements in hydraulic riveting-tools by which the rail-bonds of electric railways are riveted to the rails; and the object of the invention is to provide a tool by which the bond-rivets may be properly upset in holes punched in the flanges of girder-rails and the bases of T-rails and girder-rails, after, as well as before, the rails have been permanently laid.

On the accompanying sheets of drawings, Figure 1 is a front elevation of the tool made for riveting bonds to the flanges of girder-rails; Fig. 2, a side and sectional elevation thereof and cross-section of a fragment of a rail, the tool being shown on the rail as it is placed when about to be used. Fig. 3 is a side elevation of the tool made for riveting bonds to the bases of T-rails or girder-rails and Fig. 4 is a plan of a guide-bar and part of a clamp.

Similar reference-numerals designate like parts in different views.

This riveting-tool is used to upset the rivets of the rail-bonds in holes made in the flanges of girder-rails and the bases of T-rails or girder-rails by certain punching-tools, which are described in other applications for patents, the rails being bonded by means of these tools more conveniently, effectively, and durably than by the common practice, in which the bonds are secured to the webs of the rails.

The body of this tool resembles that of a common hydraulic riveter, it being composed, when the tool is made for riveting bonds to the flanges of girder-rails, of the short U-shaped frame 1, whose lower branch forms

upper branch of the frame 1, the entire body being a single steel casting. In the jaw 10 is a block or anvil 12, and in the cylinder 11 is a ram, in which is fixed the rivet-set 13, which 55 has a convex peen. The ram-cylinder 11 has on it two pairs of ears 14, one pair being near the top and the other near the lower end of the cylinder. The head 2 is mounted on the cylinder 11, its lower end being screwed into 60 the top of the cylinder. The head contains the pump by which the ram is actuated and with which the pump-handle 20 is connected at the back of the head, and on the top of the head is a post 21, in which is fixed a screw 22. 65 A bar 3, of which a front view, cross-section, and plan are shown in Figs. 1, 2, and 4, respectively, is fastened under the cylinder 11, on the lower ends of rods 30, which extend through the ears 14 on the cylinder and on 70 the upper ends of which is a yoke 31, the ears 14 forming guides and the rods 30 being adapted to slide therein. These rods are screwed into holes 32 in the bar 3. The axes of the holes 32 are in the plane which also contains 75 the axis of the rivet-set and are equally distant from the other axis or its prolongation. The screw 22 passes through the yoke 31, and on the screw, above the yoke, is a nut 23, which is provided with a handle 24. The central part 33 of the bar 3 is close to the frame 1, as appears by Fig. 2, and on the under side of this part of the bar, at its ends, are projections 34. The front faces of these projections are in a plane which is parallel to the 85 plane containing the axes of the holes 32 and which is at the same distance from that plane as the axes of the holes which are punched in the rails to receive the bond-rivets are from the edges of the flanges of the rails. The other 90 parts 35 of the bar 3, which extend in front of and beyond the ends of and a little below the part 33, are flat on the bottom, their under surfaces being in one plane, and in their ends are semicircular notches 36, whose curvature corresponds to that of the stems of the bond-rivets. The axes of curvature of these notches are in the plane which also contains the axis of the rivet-set, and the distance of each of them from that axis or its prolongation is the same as the distance between the axes of the rivets of the bond. Handles 37, 95 100

by which the tool may be lifted and carried, are secured to the rods 30. The ram is raised by the common means of a rack and pinion in the ram-cylinder and the lever 15, by which 5 the pinion is actuated.

The holes made in the flanges of the rails by one of the punching-tools above mentioned are tapering, being smaller at the bottom, where they conform closely to the stems of 10 the bond-rivets, than they are at the top. The bond with which two abutting rails are to be bonded is held properly under the flanges of the rails, and the rivets of the bond are pushed up through the holes until the heads 15 of the rivets are in contact with the flanges, when the stems project a little above the flanges. The riveting-tool is set on the rails so that the bar 3 rests on the flanges of the rails with the projection 34 in contact with 20 the edges of the flanges and with one end of the bar in contact with the stem of one of the rivets in one of the notches 36, the bar being on that side of the stem which is toward the abutting ends of the rails. Then, as will be 25 seen from the foregoing description, the axis of the rivet-set coincides with the prolonged axis of the other bond-rivet and the anvil 12 is directly under the head of the latter rivet. The bar 3 thus serves as a guide which facilitates 30 the proper adjustment of the tool on the rails. Then the nut 23 is turned by the handle 24 against the yoke 31, and the head and body of the tool are drawn upward until the head of the rivet which is to be upset is 35 clamped against the flange of the rail by the jaw 10 and the bar 3, the head of the rivet being on the anvil 12. By this means, too, the tool itself is clamped to the rails. It is important that the heads of the rivets should be 40 firmly held against the flanges of the rails during the riveting operation, since if they were not so held probably the heads of the upset rivets would not touch the flanges, whereas to insure a permanent proper contact between 45 the rivets and rails the flanges of the rails ought to be squeezed hard by the heads of the rivets and the upset stems. The ram is actuated by pumping water from the head into the ram-cylinder. When the rivet-set acts on 50 a rivet, it both crushes and spreads the stem, forcing the upset part of the rivet to conform to the shape of the hole from end to end, and it depresses the top of the stem a little below the top of the flange of the rail. The rivets 55 of a bond being thus upset in the abutting rails, the attachment of the bond to the rails is secure and a superior contact is established between each of the rivets and the corresponding rail, the surfaces of contact being more 60 than commonly large and the contact being very tight throughout the whole extent of those surfaces. Moreover, the rivets are so protected by the flanges of the rails that it is not likely any rivet will be subjected to pressure or a blow hard enough to loosen it.

When the tool is made for riveting bonds

to the bases of T-rails or girder-rails, its form is a modification of that shown in Figs. 1 and 2, different forms of tools being required in consequence of the difference in the forms of 70 the rails. In this modification the body of the tool, the rivet-set, and the rods on the sides of the ram-cylinder are longer, respectively, than the corresponding parts in the other form, and the tool is provided with a 75 hook 16, as appears by Fig. 3, which engages the head of the rail and helps to keep the tool in its proper position when it is to be clamped to the rail; but the modification produced by lengthening these parts and adding the hook 80 16 is substantially everything that distinguishes one form of the tool from the other. A description in detail of the construction and operation of the tool made as it is shown in Fig. 3 would be almost a repetition of the 85 foregoing description, and it is not believed to be necessary to enable the modification to be fully understood. As each of the parts shown in Fig. 3 is designated by the number of the corresponding part shown in Figs. 1 90 and 2, a comparison of each form of the tool with the other can be made and the differences between them ascertained without difficulty.

It is to be observed that whether the rails 95 bonded by this riveting-tool and the punching-tools above mentioned are girder-rails or T-rails all parts of the bonds except the stems of the rivets are underneath the flanges or bases of the rails, where they do not interfere with the fish-plates or other rail-fastenings and where they are practically safe from injury.

Having thus described my invention, what I claim as new, and desire to secure by Letters 105 Patent, is—

1. A hydraulic riveting-tool having its body composed of a united frame and ram-cylinder, the frame having a fixed jaw 10 under the ram-cylinder, said tool comprising the combination with said body, of an anvil on the jaw 10; a ram in the ram-cylinder; a rivet-set on the face of the ram; a pump connected with the ram-cylinder; and a tool-supporting device extending on opposite sides of the prolonged axis of the ram-cylinder, below the ram-cylinder and above the jaw 10, and fashioned to fit on the flanges or bases of the rails of a railway; substantially as described.

2. A hydraulic riveting-tool having its body composed of a united frame and ram-cylinder, the frame having a fixed jaw 10 under the ram-cylinder, said tool comprising the combination with said body, of an anvil on the jaw 10; a ram in the ram-cylinder; a rivet-set on the face of the ram; a pump connected with the ram-cylinder; and a tool-supporting device extending on opposite sides of the prolonged axis of the ram-cylinder, below the ram-cylinder and above the jaw 10, and fashioned to fit on the flanges or bases of the rails of a railway, and provided with means to fa-

cilitate the adjustment of the device on the rails; substantially as described.

3. A hydraulic riveting-tool comprising the combination of: a jaw and anvil on the lower part of the body; a ram-cylinder containing a ram, on the upper part of the body; a rivet-set on the face of the ram; a pump connected with the ram-cylinder; and a tool-supporting device comprising a bar extending on opposite sides of the rivet-set, and fashioned near its ends to fit on the flanges or bases of the rails of a railway, the bar having on its under side, at the back, projections 34, and in its ends notches 36; substantially as described.

15 4. A hydraulic riveting-tool having its body composed of a united frame and ram-cylinder, the frame having a fixed jaw 10 under the ram-cylinder, said tool comprising the combination with said body, of an anvil on the jaw 10; a ram in the ram-cylinder; a rivet-set on the face of the ram; a pump connected with the ram-cylinder; and a tool-supporting device extending on opposite sides of the prolonged axis of the ram-cylinder, below the ram-cylinder and above the jaw 10, and fashioned to fit on the flanges or bases of the rails of a railway, this device being movable with respect to the body and being one member of a clamp, the other member of which is the jaw and anvil; substantially as described.

30 5. A hydraulic riveting-tool having its body composed of a united frame and ram-cylinder, the frame having a fixed jaw 10 under the ram-cylinder, said tool comprising the combination with said body, of an anvil on the jaw 10; a ram in the ram-cylinder; a rivet-set on the face of the ram; a pump connected with the ram-cylinder; and a tool-supporting device extending on opposite sides of the prolonged axis of the ram-cylinder, below the ram-cylinder and above the jaw 10, and fashioned to fit on the flanges or bases of the rails of a railway, and provided with means to facilitate the adjustment of the device on the rails, and this device being movable with respect to the body and being one member of a clamp, the other member of which is the fixed jaw and anvil; substantially as described.

45 6. A hydraulic riveting-tool comprising the combination of: a jaw and anvil on the lower part of the body; a ram-cylinder containing a ram, on the upper part of the body; a rivet-set on the face of the ram; a pump connected with the ram-cylinder; and a tool-supporting device constituting also a member of a clamp, the other member of which is the jaw and anvil, this device comprising a bar extending on opposite sides of the rivet-set, and fashioned near its ends to fit on the flanges or bases of the rails of a railway, the bar having on its under side, at the back, projections 34, and in its ends notches 36; substantially as described.

60 7. A hydraulic riveting-tool comprising the combination of: a jaw and anvil on the lower part of the body; a ram-cylinder containing

a ram, on the upper part of the body; a rivet-set on the face of the ram; a head containing a pump, on the ram-cylinder; and a device consisting of a bar extending on opposite sides of the rivet-set, rods connected with the bar and held in guides on the ram-cylinder, a yoke on the upper ends of the rods, and means for raising the head and body of the tool supported by the yoke, rods and bar; substantially as described.

70 8. A hydraulic riveting-tool comprising the combination of: a jaw and anvil on the lower part of the body; a ram-cylinder containing a ram, on the upper part of the body; a rivet-set on the face of the ram; a head containing a pump, on the ram-cylinder; and a device consisting of a bar extending on opposite sides of the rivet-set, rods connected with the bar and held in guides on the ram-cylinder, a yoke on the upper ends of the rods, a screw fixed on the head and extending through the yoke, and a nut on the screw above the yoke; substantially as described.

80 9. A hydraulic riveting-tool comprising the combination of: a jaw and anvil on the lower part of the body; a ram-cylinder containing a ram, on the upper part of the body; a rivet-set on the face of the ram; a head containing a pump, on the ram-cylinder; and a device consisting of a bar extending on opposite sides of the rivet-set, rods connected with the bar and held in guides on the ram-cylinder, a yoke on the upper ends of the rods, a screw fixed on the head and extending through the yoke, 90 and a nut on the screw above the yoke, the bar being fashioned near its ends to fit on the flanges or bases of the rails of a railway, and having on its under side, at the back, projections 34, and in its ends notches 36; substantially as described.

95 10. A hydraulic riveting-tool having its body composed of a united frame and ram-cylinder, the frame having a fixed jaw 10 under the ram-cylinder, said tool comprising the combination with said body, of an anvil on the jaw 10; a ram in the ram-cylinder; a rivet-set on the face of the ram; a pump connected with the ram-cylinder; and a tool-supporting device fashioned to rest on the work in which the rivets are secured, at points on opposite sides of the rivet-set and on both sides of a transverse plane containing the axis of the rivet-set; substantially as described.

110 11. A riveting-tool comprising the combination of: a jaw and anvil on the lower part of the body; a rivet-set, and its operating mechanism in the upper part of the body; and a tool-supporting device fashioned to fit on the flanges or bases of the rails of a railway, 115 at points on opposite sides of the rivet-set and on both sides of a transverse plane containing the axis of the rivet-set; substantially as described.

120 12. A riveting-tool comprising the combination of: a jaw and anvil on the lower part of the body; a rivet-set, and its operating

mechanism in the upper part of the body; and a tool-supporting device fashioned to fit on the flanges or bases of the rails of a railway, at points on opposite sides of the rivet-set and 5 on both sides of a transverse plane containing the axis of the rivet-set, this device being movable with respect to the body of the tool and being one member of a clamp, the other member of which is the jaw and anvil; substantially as described.
